UNITED STATES PATENT OFFICE.

NELLIE C. LARSON, OF MEDICINE HAT, ALBERTA, CANADA.

COMBINATION IRONING BOARD AND CLOTHES DRIER.

Application filed June 5, 1925. Serial No. 35,205.

This invention relates to a combined ironing board and clothes drier.

An important object of the invention is to provide a laundry apparatus wherein the ironing board supporting frame may be readily converted into a clothes drying rack.

A further object of the invention is the provision of a device of the above character embodying a firmly supported ironing board.

10 A still further object of the invention is the provision of an ironing board stand of durable construction readily convertible for use as a clothes drier.

15 A still further object of the invention is the provision of apparatus of the above mentioned character which is comparatively simple yet durable of construction and which can be placed upon the market at a relatively low cost.

20 Other objects and advantages of this invention will become apparent as the description progresses.

In the accompanying drawings forming a part of this specification and in which like numerals are employed to designate corresponding parts throughout the same:

25 Figure 1 is a side elevation of the apparatus constructed in accordance with my invention arranged for use as an ironing board and stand,

Figure 2 is a top plan view of the same,

Figure 3 is an enlarged detailed view showing one of the members for connecting the board with the stand,

30 Figure 4 is a side elevation of the stand shown in operative position as a clothes drier,

Figure 5 is an end elevation of the same, and

40 Figure 6 is an enlarged perspective view of an adjustable bracket member used in connection with my apparatus.

In the drawings, wherein for the purpose of illustration is shown the preferred embodiment of my invention, the numeral 10 generally designates the convertible supporting stand of the structure composed of pivotally connected sections 11 and 12. Each of these sections embodies a pair of longitudinal side bars 13 preferably constructed of wood and rectangular in cross section. These bars are arranged in parallel relation and are connected by a plurality of transversely extending rungs 14. These rungs are arranged equi-distantly between the side bars 13 and may also be of wood,

It is to be noted that one of the stand sections 12 is of slightly narrower construction than the complementary section 11 so as to permit convenient pivotal connection of the sections. The sections are connected at their upper extremities by means of a transversely extending pivot rod 15 extending through openings formed in the upper ends of the side bars 13 of the sections and through a pair of spacing collars 16 positioned between the side bars of the sections.

Means are provided for connecting the sections so as to retain the same in adjusted position, this being accomplished by the provision of a pair of brace bars 17 pivoted to the section 11 adjacent the upper ends of the side bars and each provided with a notch 18 adjacent their outer free ends.

These outer ends of the bars are engageable with pins 19 secured to the side bars of the sections 12 and extending outwardly therefrom so that the outer notches 18 of the brace bars may be brought into engagement with these pins for retaining the sections in relatively adjusted positions.

The brace bars 17 are also provided with intermediate notches 20 the purpose of which will become apparent as the description progresses.

In its erected position as shown in Figs. 1 and 2 the stand 10 is arranged so that the lower ends of the side members of the section 11 rest on the floor, the section extending vertically, while the complementary section 12 extends horizontally at right angles to the section 11. The sections are retained firmly in this position of adjustment by means of the brace bars 17.

Securely mounted on the outer free end of the section 12 of the stand 10 is an ironing board 21, the end portions of which are preferably rounded as clearly illustrated in Figures 1 and 2, this board preferably being of wooden construction. Secured to the under side of the ironing board 21 and positioned so as to engage the outer free ends of the side members 13 of the stand section 12 are two pairs of yokes 22 of U-shaped formation provided with outwardly directed flanges for connection with the ironing board. The U-shaped body portions of the yokes are slidable, engageable with the side members of the horizontal section 12, the yokes snugly engaging the said side members so as to firmly retain the board on the stand. It is necessary to further

brace the ironing board by resting the same against a suitable projection upon a wall, as a shelf, or by resting the outer shelf portion of the board upon the edge of a table 5 as 22'.

It can be readily seen from the foregoing description, that an ironing board and stand of compact construction is provided, the horizontal section 12 of the ironing board 10 stand providing a support for the articles as they are ironed to prevent soiling by contact with the floor. The provision of this extension will facilitate the ironing and at the same time serve as a protection for the articles being ironed.

It is furthermore contemplated to employ the stand 10 as a clothes drying rack, this being accomplished by removing the ironing board 21 from the end of the section 12 and 20 shifting the brace bars 17 so that the pins 19 on the section 12 will engage the intermediate notches 20 of the bracket bars. The sections are thus adjusted from a right angular position to oppositely inclined positions 25 and the free ends of the sections are placed in contact with the floor. This provides a rack, as clearly illustrated in Figures 4 and 5, upon which articles may be placed and quickly dried. It is obvious from the foregoing, that the stand 10 may be readily converted to serve a dual purpose, in the first instance as an ironing board supporting stand and clothes retaining extension and, in the second instance, as a clothes 30 drying rack. When the apparatus is not 35

in use in either capacity, the sections may be collapsed and the ironing board removed so that the apparatus may be stored in a comparatively small space.

It is to be understood that the form of 40 my invention herewith shown and described is to be taken as the preferred example of the same and that various changes as to the shape, size and arrangement of parts may be resorted to without departing from the 45 spirit of the invention, or the scope of the subjoined claim.

Having thus described my invention, I claim:

In a device of the class described, a stand 50 structure comprising a pair of sections hingedly connected end to end for relative angular adjustment whereby the sections may be positioned to extend one horizontally and the other vertically, the vertically extending section constituting a support for the horizontal section, means relatively bracing the sections and pivotally connected with one section and separably engaged with a part of the other section, the horizontal section including spaced side members, an ironing board, and spaced pairs of yokes upon the under side of the ironing board 55 slidably engageable with the side members of the said horizontal section for separably connecting the ironing board with the said section to be supported thereon.

In testimony whereof I affix my signature.

(MRS.) NELLIE C. LARSON.
